UNITED STATES PATENT OFFICE.

WILLIAM A. MORRISON, OF BOSTON, MASSACHUSETTS.

HYGIENIC MITTEN.

1,053,204.

Specification of Letters Patent.

Patented Feb. 18, 1913.

Application filed October 12, 1910. Serial No. 586,681.

To all whom it may concern:

Be it known that I, WILLIAM A. MORRISON, of Boston, in the county of Suffolk and State of Massachusetts, have invented certain new and useful Improvements in Hygienic Mittens, of which the following is a specification.

The object of the present invention is to provide a guard for the hands for hygienic and curative purposes, in order to facilitate the cure of skin diseases and eruptions which produce itching. In order to cure such diseases and affections it is essential that the skin should not be broken or scratched, but to make the persons afflicted with such trouble refrain from scratching is difficult, and in the case of children, impossible. Moreover during sleep adults as well as children are liable to scratch the affected places unconsciously and involuntarily.

It is the object of my invention to provide a guard which will make scratching impossible by surrounding the hand with an envelop the surface of which is at once so smooth and soft that it cannot injure or irritate the affected part of the skin, no matter how hard it may be pressed against the affected place, while it is at the same time of such nature that it will distribute the pressure of a finger end or knuckle and make it impossible for the patient to apply a sufficiently hard and localized pressure at any point to produce injury.

One of the forms in which my invention is reduced to practice is illustrated in the drawings, in which—

Figure 1 represents a side elevation of a guard suitable for the purpose. Fig. 2 represents an elevation of the guard from a position at right angles to the view point of Fig. 1. Fig. 3 is a cross-section of the guard.

The same reference characters indicate the same parts in all the figures.

Briefly stated the guard consists of an inner sack or mitten *a* which is designed to fit somewhat closely about the closed hand, and an outer cover *b* separated from the inner sack, which also may be termed the lining, on all sides by a space *c* which is adapted to contain air under pressure and form a pneumatic envelop. The guard as a whole is adapted to be drawn over the hand in the manner of a glove or mitten, the inner sack or lining thereof fitting the

hand. This inner member may be made in the form of a glove having digitations to receive the fingers and thumb, or of a mitten with a separate pocket for the thumb only, or, as here shown, as a bag in which the fingers and thumb are all contained. 60

The lining *a* and outer cover *b* are made of some material impervious to air, such as rubber, fabric impregnated with rubber, or any other material known to the arts and having the desired qualities. This material may be more or less elastic or wholly inelastic, if desired. 65

Attached to the cover *b* and communicating with the intermediate space *c* is an air valve *d* through which air may be blown to fill the air space and inflate the outer envelop. The air pressure is preferably raised to such a point that the wearer of the mitten will be unable to protrude a finger or knuckle across the air space and against the external covering so as to form a hard point capable of scratching the skin. Motion of the lining as a whole toward either side of the outer cover is prevented by stay pieces 70 which retain the inner member centrally within the outer member and preserve the air space of uniform thickness on all sides. 75

The spacers may be of any suitable character, those which I have illustrated being strips connected at their opposite edges to the inner and outer members respectively, and crossing the air space, one of such strips, as *e*, being carried from the back of the mitten around the end to the front side, and another, as *f*, being carried from one side to the other also around the end. More than two such strips may be employed if desired and the arrangement may be varied from that shown according as the needs of any 80 particular case require. Where the spacing strips are disposed as here shown, they terminate short of the wrist end of the envelop so that the air admitted to the valve may flow into all of the compartments of the air space which are divided from one another by the spacing strips. These strips may also be apertured to permit free flow of air through them. The strips may be very soft and flexible, and must not be so 85 stiff as of themselves to scratch the skin. Provided they have sufficient tensile strength to tie the inner and outer members of the guard together, they need have no appreciable stiffness. 90

Conveniently a cross bar *g* may be held at its ends within the inner member so as to cross the same in such position that it may be grasped by the hand.

5 The main feature of the present invention is that it provides a soft envelop which entirely surrounds the hand on every side so that nowhere is any hard or harsh point left capable of injuring the skin in the manner 10 above noted.

I claim,—

1. A hand guard comprising an air tight sack provided with a wrist opening and shaped to form an interior chamber in which 15 the hand is adapted to be moved freely, and an outer air tight cover inclosing said sack except at the wrist opening and separated from the sack at all points by an air space, whereby a soft and yielding exterior surface 20 is provided, and longitudinally disposed stays uniting said sack and said outer cover, a space being formed between the ends of said stays and the rear wall of said cover,

whereby pressure in said air space is equalized.

2. A mitten or hand-guard for use in the treatment of skin diseases, comprising an inner sack adapted to surround the hand of the patient and having a wrist opening, an outer sack of a soft and flexible material 30 impervious to air, enveloping the inner sack and in air tight connection therewith adjacent to the wrist portion, there being an inflatable air space between the inner and outer sacks at all points except the wrist 35 connection, and separated flexible stays crossing the air space, so disposed at all sides of the mitten as to prevent any part of the hand within exerting concentrated pressure through the outer sack.

In testimony whereof I have affixed my signature, in presence of two witnesses.

WILLIAM A. MORRISON.
